UNITED STATES PATENT OFFICE.

JACOB RUPPERT SCHALK, OF RHINEBECK, NEW YORK.

DESIGN FOR A MARINE RAIL STANCHION.

Application filed April 4, 1928. Serial No. 26,124. Term of patent 14 years.

To all whom it may concern:

Be it known that JACOB RUPPERT SCHALK, a citizen of the United States, residing at Rhinebeck, in the county of Dutchess and State of New York, has invented a new, original, and ornamental Design for a Marine Rail Stanchion, of which the following is a specification, reference being had to the accompanying drawing, forming part thereof.

Figure 1 shows a side elevation of the article, showing my new design.

Figure 2 shows a front elevation of the same.

Figure 3 shows a cross sectional view on the line A—A.

Figure 4 shows a cross sectional view on the line B—B.

I claim—

The ornamental design for a marine rail stanchion, as shown.

JACOB RUPPERT SCHALK.
